UNITED STATES PATENT OFFICE.

EUGENE OSCAR ENGELS, OF SAGINAW, MICHIGAN, ASSIGNOR TO BAKER-PERKINS COMPANY, INCORPORATED, OF WHITE PLAINS, NEW YORK, DOING BUSINESS AT SAGINAW, MICHIGAN.

GAS CONTROL FOR OVENS.

Application filed March 16, 1926. Serial No. 95,162.

This invention relates to gas-heated ovens and more particularly to certain improvements in the gas-and-air supply conduits to the burners.

5 The object of my improvement is to reduce the likelihood of accumulating combustible gases within the oven and the consequent danger of explosion, especially while the oven is being lighted.

10 A further object is to provide a pressure relief device in the gas-and-air conduit, which, by its construction and mode of operation, is especially well adapted for use in conjunction with the means commonly employed for automatic gas-and-air mixture control. Control apparatus of this character is well known in the art, being commonly installed as a part of the premixing gas system of baking ovens. For a typical automatic mixture control of the kind referred to reference may be had to United States patents to Keith, Numbers 1,250,319 and 1,301,272. The object of my present improvement is to make the operation of the 15 automatic mixture control device more dependable under certain conditions of mixture pressure at the burners.

This invention is the result of extensive investigation and research into the operation of gas burners in bake ovens of various types, such as traveling tray, chain, or plate ovens, and peel and draw plate ovens.

Although extremely simple, both in installation and theory, my invention has 30 solved satisfactorily one of the most perplexing problems that has confronted baking equipment engineers. I refer to the problem of quickly and safely lighting a great number of burners when fed by an automatic mixture control device and while the burners are surrounded by steam or extremely moist air. My improvement avoids liability of explosion.

With the foregoing and certain other objects in view, which will appear later in the specification, my invention comprises the devices described and claimed and the equivalents thereof.

In the drawings, Fig. 1 is a side elevation 35 of a baking oven embodying my improvement.

Fig. 2 is a top plan view, on an enlarged scale, showing a back corner of the oven and

part of one burner, together with the gas supply line as ordinarily connected thereto. 55

To clearly set forth the novelty and utility of my improvement, I will first explain the shortcomings of bake oven operation that prompted the research which resulted in this invention. 60

Traveling tray ovens and other bake ovens commonly have been equipped with unit premixing gas systems and automatic mixture controls of the general type shown in the Keith patents referred to. Such a control device, diagrammatically indicated by numeral 1, is usually located near the outside wall 2 of a bake oven. It is supplied through a pipe 3 with compressed air and through pipe 3^a with gas. Mixing is effected while 65 both air and gas are being passed through a suitable injector 4, into a header or supply conduit 5, from which branch pipes 6 lead to burner pipes 7 having the usual burner slots 70 8. Each branch pipe 6 has an individual burner shut-off cock 9.

Preferably there is one such mixture control device 1 for each header 5 which in turn supplies several burners, usually six to 75 seventeen. 80

The control device is supposed to maintain the mixture at a constant gas-air ratio, regardless of variations in pressure in the header 5 as long as these variations are kept within certain limits, namely, the pressure 85 of the gas when normally entering the burner. In practice, however, it works satisfactorily only so long as the pressure in the header 5 does not exceed the pressure needed during the time the majority of the burners 90 connected to that header are open. When some of the burners are turned off the pressure in header 5 gradually increases, decreasing the injector suction and finally changing from suction to pressure. The injector 4 95 then fails to entrain any gas, thereby unbalancing the gas-air ratio. When this occurs it is impossible to obtain a proper mixture at the burner or even to light the system, without first opening the majority of the 100 burners, so as to reduce the header pressure below the stated limit.

All burner shut-off cocks 9 were usually kept open. To light the oven the mixture supply was admitted from injector 4 to 105 header 5 and into the oven through all the

burner pipes 7. Even a little delay in lighting the burners caused trouble, for it is practically impossible to light the burners quickly enough by hand to avoid explosion.

5 All methods heretofore employed for lighting involved a certain amount of risk, because the most skillful operator may not notice in time that the burners fail to light, and it may then be too late to prevent an 10 accumulation of explosive gas.

Pilot flames have failed, because an ordinary gas flame does not burn in an oven filled with steam and products of combustion.

15 Electric spark ignition at each burner has been used, but even the best electric lighter occasionally fails to work under heavy steam conditions in the oven.

The safest way to light an oven is to 20 ignite only one burner at a time, giving the operator a chance to see that it is properly lighted before turning on the next. For reasons previously stated, lighting one burner at a time is not practicable when 25 the unit control device 1 is employed, unless the building up of pressure in the header with its consequent disarrangement of the gas-air ratio is prevented. Many attempts have been made to increase the working 30 range of the gas-air control device 1, and thereby correct that inherent defect of the control system.

One method was to reduce the air pressure at the entrance to the injector by automatic 35 regulation of the air pressure. This resulted in an expensive, delicate and complicated apparatus having serious disadvantages, one of which is the necessity of installing a gas blower in addition to the usual air fan. Such 40 an attempt is described in Keith's British Patent 226,298, September 25, 1923.

45 My study and research which brought forth the present invention was directed to finding a simple means for counteracting the building up of the pressure within header 5 when most of the burners were shut off. It resulted in installing a pressure-relief device at any convenient point of the gas-air header 5, so as to let a part of the unburned mixture vent to the atmosphere when the pressure exceeds a predetermined amount, viz, just sufficient to supply all the 50 burners of header 5 simultaneously.

It has been used successfully and affords 55 a complete, simple and satisfactory solution of the problem of accident hazard in lighting bake oven burners.

The essential structural differences that 60 mark an oven embodying my invention from the same oven as heretofore commonly used, are found in the pipe lines that lead from the automatic mixture control device and supply the combustible mixture of air and gas to the numerous burner tubes within 65 the oven.

A relief valve 11 located at any convenient place, and, communicating with header 5 constitutes my preferred means for relieving the pressure within the header. The gas may escape through a vent pipe 10, preferably leading to the open air. 70

The operation is as follows:

Before the oven is started all the individual burner cocks 9 are closed. The pre-mixer 1 is put into operation in the usual 75 manner. The gas and air mixture, having no access to burners 8, increases its pressure within the header 5 and thereupon a small quantity of the combustible mixture escapes into the open air through vent pipe 10. Relief valve 11 is adapted to open at a pressure that has been found by trial to be within the pressure range of proper operation of the control device 1. 80

One burner at a time is then opened and lighted before the next is turned on. The additional escape of gas-air mixture through the burner 8 when it is turned on causes a further drop of pressure in the header 5. The relief valve 11 thereupon 90 partly closes and proportionally reduces the escape of mixture to the atmosphere.

When the majority of the burners on a header have thus been turned on and lighted, the pressure in the header pipe 5 has dropped sufficiently to close relief valve 11. 95 When all burners on header 5 have been lighted the pressure within the header becomes still lower and thereafter there will be no automatic opening of valve 11 during 100 the normal operation of the oven.

Pressure in header 5 under actual operating conditions is usually between three inches and four inches of water column. Relief valve 11 is generally set to open at 105 seven to eight inches water column, hence is kept tight when all burners are turned on. The loss of gas is negligible, since it does not occur except during the lighting of the burners, only a few seconds for each, and because separate burners are never turned off during operation. The heat control of the oven is attained, as formerly, by regulating the air pressure to the gas-air header 5. 110

Possible leaks through the relief valves 11, caused by grit or dust on the valve seat are prevented by providing in the vent pipe 10 a hand-operated valve 13, which is opened only while the oven is being lighted, 120 and is closed during normal operation.

Obviously other means than check valves 11 may be employed for gas pressure relief, and I have employed various diaphragm valves and other devices for this purpose, but find in practice that the ordinary type swing check valve is entirely suitable. 125

The "unit" control system, that is, the system in which the control devices 1 are employed on each header 5, is thus relieved 130

of the limitations heretofore imposed upon it because of building up pressure within the header to a degree that resulted in loss of control of the gas-air ratio and consequent inoperativeness of the gas mixing devices, especially during the starting of an oven.

With my improvement the system can be lighted by the usual bake oven gas torch or projection flame without any danger, in cases where no electric lighter is available.

While I have shown and described the invention as applied to a baker's tray oven, it is to be understood that it is equally applicable to any kind of gas heated oven or heater in which a gas mixture control device or automatically controlled premixing device is employed, its function being to increase the efficiency and field of usefulness of such gas-air mixture control devices, as has been set forth herein.

Having thus described my invention, what I claim and desire to secure by Letters Patent is:

1. In combination, a heating chamber having a plurality of burners, a header adapted to supply combustible mixtures of air and gas to said burners, a valve-con-

trolled gas conduit connecting each burner with said header, a pressure-regulated automatic mixture control device adapted to supply gas and air in predetermined ratio to said header during normal variations of pressure therein, and independent automatic means for relieving the pressure within said header before said pressure can rise sufficiently to interfere with said normal operation of said mixture control device.

2. In combination, a heating chamber having a plurality of burners, a header adapted to supply combustible mixtures of air and gas to said burners, a valve-controlled gas conduit connecting each burner with said header, a pressure-regulated automatic mixture control device adapted to supply gas and air in predetermined ratio to said header during normal variations of pressure therein, and a relief valve communicating with and adapted to vent said header when the pressure therein rises sufficiently to interfere with said normal operation of said mixture control device.

In testimony whereof, I affix my signature.

EUGENE OSCAR ENGELS.
